GAS ENTRAINED LUMP-BREAKING AND DRYING EQUIPMENT

Robert Laurance Morrison, Blairmore, Alberta, Canada, assignor to West Canadian Collieries, Limited, Blairmore, Alberta, Canada, a corporation of Canada

Application January 13, 1954, Serial No. 403,839

6 Claims. (Cl. 241—40)

This invention relates to apparatus for the rapid and continuous drying of finely divided materials by the direct heat exchange with hot gases at high velocities. The apparatus relates more particularly to improvements in fluidized or gas entrained drying equipment.

Apparatus for drying finely divided solids in a high velocity stream of hot gases is generally known. Such apparatus consists of a combustion furnace for generating hot gases, a drying chamber for entraining finely divided material in an uprising stream of the hot gas, and a separator for separating dried material from the spent gases issuing out of the drying chamber. In such apparatus the hot gases from the combustion furnace are passed through a rather narrow passage or neck upwardly into a drying chamber. The wet, finely divided material is introduced into the drying gases in the neck, so as to suspend the material in the rising hot gases. The neck expands and connects with the body of the drying chamber above the point of solids introduction. The suspended solids are maintained in a fluidized or gas entrained state in the enlarged portion of the drying chamber until the particles become substantially dry, at which point the dried solid material is carried up and out of the drying chamber. A separator then recovers the dried product from the spent gases.

The present invention provides an improvement over the known driers of the prior art. In the driers as known, there is a grading or other pressure or velocity equalization constriction means across the hot gas inlet into the drying chamber. These constrictions tend to aid the entrainment of the solids in the gas. With certain operations, however, very wet coal is encountered, especially where low rank coal has been extensively washed to remove rock and ash impurities. The coal discharged from such a washing operation is of the character of a sludge, which cannot be dewatered within practical limits by mechanical means. The sludge packs or lumps into large particles which are not readily entrained and dried in the drying chamber, and drop through the entraining constrictions, out of the drying chamber. Feed devices have been suggested for breaking up the lumps, however, these have not been practical. It is an object of the present invention to provide an improved device for the fluidized or gas entrained heat transfer or drying of finely divided wet solids.

It is another object of the invention to provide a simple and efficient feed mechanism for wet coals and the like for hot gas driers.

It is still another object of the present invention to provide an improved method of the entraining of finely divided wet solids in a stream of hot gases.

These and other objects of the invention will be readily apparent by referring to the following description and appended drawings in which:

Fig. 1 is a sectional view of the device according to the invention, including a partial view of auxiliary equipment used with the device.

2

In the device selected for illustration, a combustion furnace 10, only partly shown in Fig. 1 as it does not form a part of the invention, provides a stream of hot gases for drying solid material. The hot gases sweep down the furnace 10 around a bend 11 into a neck 12 of a drying chamber 17. Swirl producing vanes 14 at the lower end of an entraining portion 15, violently swirl the hot gases, and baffles 16 directly above the vanes tend to straighten the whirling gases into straight line flow up the drying neck 15. The swirl vanes and baffles aid in providing a uniform pressure or velocity gradient across the entraining neck 15, for more efficient material spread and, therefore, more efficient drying. Wet coal is fed by the feed means 28 into the entraining chamber 15. The wet solid is dropped generally toward the swirl and baffle means, and is picked up in the hot gases in the swirl means and is entrained in the gases rising up through the chamber 15.

A by-pass 18 passes around the swirl producing means 14 and the baffles 16 and exhausts immediately adjacent the feed means outlet 30 in chamber 15. The inlet 20 to the by-pass 18 is flared to act as a scoop for the hot gases through the by-pass. The resistance to flow through the by-pass 18 is less than through the swirl producing means, and so a part of the gas will pass through the by-pass means. The by-pass is small enough, however, that the majority of the gas passes through the swirl vanes for entraining solids fed into the drier. The outlet 22 of the by-pass 18 is flattened to substantially increase the velocity of the by-passed gas issuing from the outlet 22. The feed means 28 consists of a screw conveyor which has an outlet 30 along the wall of the drier. The wet material being exhausted from the feed outlet 30 falls directly into the jet stream issuing from outlet 22, and is picked up in the jet stream and carried across the drying column and forcefully thrown into the wall at about point 24. The lumps which hit the wall are effectively broken up and as they fall from their contact with the wall they are picked in the gas stream and are entrained for drying.

40 A spiral conveyor 32 is provided directly beneath the drying chamber inlet 15 to remove ash brought over by the hot gases from the combustion furnace 10 and any large lumps of the material which may drop through the swirl producing means 14.

45 In general, the by-pass 18 provides a smooth, circular conduit for passing a portion of the hot combustion gases around the swirl producing means into the entraining chamber at 15. The by-pass is flattened and somewhat reduced in area at the outlet 22 so as to form a gas jet stream of high velocity directly next to the outlet 30 of the feed means 28. The flattened end 22 extends substantially across the diameter of the outlet 30, so that any coal dropping from the feed means will be picked up in the jet stream and will be forced across the drying chamber onto the wall 24. This jet stream insures all material issuing from the feed means will be broken into small particles for entrainment in the rising stream of hot gases.

Others may readily adapt the invention to various conditions and various modes of operation without departing from the spirit and the scope of the invention. It will be apparent to those skilled in the art that the invention may be modified without departing from the inventive concept.

65 I claim:

1. In apparatus for drying subdivided materials in a gas entrained state, an upright drying column, means for introducing heated gases into the lower end of said column, means for introducing material in subdivided condition into said column above its bottom adjacent the side wall thereof, a series of vanes in said column intermediate said means for introducing said gases and said

material for entraining said material in said gas, and a by-pass duct means interconnected with said column for conducting a portion of said heated gases around said vanes, said duct means having a flared inlet forming a scoop interconnected with and adjacent the lower end of said column and a constricted outlet adjacent the material inlet to said column, said outlet being arranged to provide a high velocity stream of gas directed transversely across said column whereby material may be entrained in said gas stream therefrom and be forced against the opposite wall to break up lumps of particles to be suspended in said gases.

2. In apparatus for drying subdivided materials in a gas entrained state, an upright drying column, means for introducing heated gases into the lower end of said column, means for introducing material in subdivided condition into said column above its bottom adjacent the side wall thereof, swirl producing means in said column intermediate said means for introducing said gases and said material, and by-pass duct means interconnected with said column for conducting a portion of said heated gases around said swirl producing means, said duct means having a flared inlet forming a scoop interconnected with the lower end of said column and a restricted outlet interconnected with said column below and adjacent the material inlet to said column, said outlet being arranged to provide a high velocity stream of gases directed transversely across said column whereby material may be forced against the opposite wall to break up lumps of particles to be suspended in said gases.

3. In apparatus for drying subdivided materials in a gas entrained state, an upright drying column, means for introducing heated gases into the lower end of said column, screw conveyor means for introducing material in subdivided condition into said column above its bottom adjacent the side wall thereof, velocity equalizing means in said column intermediate said gas introducing means and said conveyor means for entraining material uniformly across said column, and a by-pass duct for conducting a portion of said heated gases around said velocity equalizing means, said duct having a flared inlet forming a scoop communicating with the lower end of said column and a restricted outlet communicating with said column adjacent the material inlet, said outlet being arranged to provide a high velocity stream of gases directed transversely across said column whereby material from said screw conveyor means may be entrained and forced against the opposite wall to break up lumps of particles to be suspended in said gases.

4. In apparatus for drying subdivided materials in a gas entrained state, an upright drying column, means for introducing heated gases into the lower end of said column, means for introducing material in subdivided condition into said column above its bottom, swirl imparting means in the column intermediate said means for introducing gases and material and arranged to impart

centrifugal movement to a portion of the entering gas to entrain said solids, and by-pass duct means interconnecting the lower end of said column with a point thereabove for conducting the remainder of the entering gas around said swirl means, said duct means having an outlet communicating with said column below and in proximity to the material introduction means arranged to entrain material in a stream from said duct and direct it onto the column wall for breaking up lumps of material for suspending the same in said gases.

5. In apparatus for drying subdivided materials in a gas entrained state, an upright drying column, means for introducing heated gases into the lower end of said column, means for introducing material in subdivided condition into said column above its bottom, swirl imparting means and baffle means in the column intermediate said means for introducing said gases and material to entrain solids uniformly across said chamber, and by-pass duct means interconnecting the lower end of said column with a point above said swirl imparting and baffle means for conducting the remainder of the entering gas around said swirl means, said duct means having an outlet located below and in proximity to the material introduction means arranged for breaking up lumps of material and for suspending the same in said gases.

6. In apparatus for drying subdivided materials in a gas entrained state, an upright drying column, means for introducing heated gases into the lower end of said column, screw conveyor means for introducing material into subdivided condition into said column above its bottom, said conveyor means exhausting adjacent the wall of said column, swirl imparting means in the column intermediate said points of introduction constructed and arranged to disperse the divided material across the column, and by-pass duct means interconnecting the lower end of said column and an upper portion thereof for conducting a portion of said heated gases extending around said swirl means, the outlet of said by-pass duct means being restricted for providing a high velocity stream of gas below said conveyor whereby material from the conveyor means is carried across the chamber and impacted into the opposite wall to break up lumps of material to be suspended.
